UNITED STATES PATENT OFFICE.

JOHN T. HORTON, OF NEW YORK, N. Y.

FALL-ROPE CARRIER.

1,108,368.

Specification of Letters Patent. Patented Aug. 25, 1914.

Application filed November 21, 1912. Serial No. 732,704.

To all whom it may concern:

Be it known that I, JOHN T. HORTON, a citizen of the United States, and a resident of New York, borough of Brooklyn, in the county of Kings and State of New York, have invented certain new and useful Improvements in Fall-Rope Carriers, of which the following is a specification.

This invention relates to fall rope carriers and has for its object to provide a device of the class specified in which the moving parts are mounted and guided for free movement and in which the friction incident to such movement is reduced to a minimum.

My invention is in the nature of improvements upon the device of United States Patent 1003261, granted September 12, 1911, to Horton and Deline.

In the drawings accompanying this specification I have illustrated the preferred embodiment of my improvements wherein—

Figure 1 is a side elevation of a fall rope carrier. Fig. 2 is an elevation, partly in section, of what is shown in Fig. 1. The section is taken on line 2, 2 of Fig. 1. Fig. 3 is a detail view, partly in section, corresponding with the lower part of Fig. 2. Fig. 4 is a rear view of a portion of what is shown in Fig. 1.

As the general function of fall rope carriers is well known it is deemed unnecessary to illustrate the present device in connection with other parts of the cable way or to describe other than briefly, the general operation of such a carrier.

One of the objects of the present improvements is to reduce friction and undue wear in the parts thereof due to a tendency of the driving or traction line 4 to deflect the floating frame, including members 5, 6, 7 and 8, from its normal general plane of movement.

Another object of my improvements is to prevent the return run 4^a of traction line 4 and the hoisting or fall rope 9, from becoming unseated in their respective supporting wheels 10, 11.

Mounted in main frame 12 are two cable traverse wheels 13, 14 and depending from said main frame between said wheels is frame member 15 rotatably mounted in which are wheels 10 and 11 above referred to. Traverse wheels 13, 14 engage and are supported by the usual main cable 16. Co-axially fixed relatively to wheels 13, 14 are drive wheels as 17 and rotatably supported

on swingable arms 5, 6 pivoted to main frame 12 are gripper wheels 19, 20 respectively for engagement with the underside of cable 16. Tension wheel 31 is rotatably mounted in the upper ends respectively of links 7 and 8 and the lower ends of said links are pivotally attached to arms 5, 6, preferably coaxially with gripper wheels 19, 20, respectively.

As traction line 4 is necessarily located at one side of the vertical plane through main cable 16 the tendency of that traction line is to deflect to the right, Fig. 2, the upper part of the floating frame comprising members 5, 6, 7 and 8 and to deflect to the left the lower parts of that floating frame. For maintaining said floating frame, including swingable arms 5, 6, in its normal plane of movement and for preventing sidewise deflection thereof I provide means including a resistance bar 25 which may be conveniently bolted to rear member 15^a of frame 12 with the outreaching ends of that bar in close proximity to the heads as 26 of pivotal bolts 21 and 23 whereby said bolt heads and rear swingable arms 5^a, 6^a are permitted free movement in their normal plane of action but are prevented from deflection to the left, Fig. 2. By this means any tendency of swingable arms 5, 6 to deflect to the left, Fig. 2, is prevented.

Just above rope supporting wheel 11, which wheel is conveniently grooved for the reception and support of rope 9 I rotatably mount wheel 27 on bolt 28 extending from frame 15 to frame member 15^a. Said wheel 27 may be provided with an extended cylindrical face as shown in Fig. 2 or it may have a narrow cylindrical face extending into the groove of wheel 11 as shown in Fig. 3. Also said wheel 27 is preferably mounted for free movement lengthwise its axis as illustrated, so as to permit even wear on its cylindrical surface. Also as this wear is rather severe I preferably mount said wheel upon an eccentric bushing 29 so that by loosening the nut of bolt 28 said bushing may be rotated to adjust wheel 27 relatively to rope supporting wheel 11. Rope supporting wheel 10 may also be provided with a second wheel 30 for engagement with its rope 4^a for holding said rope in engagement with supporting wheel 10.

I claim:

1. A fall rope carrier including in combination, two supporting cable traverse

wheels rotatably mounted in fixed relation to each other, a gripper wheel for engagement with the under side of the supporting cable and rotatably mounted in the free end 5 of a swingable arm, a tension wheel for engagement with the upper side of said driving line and rotatably mounted in the upper end of a second swingable arm, the free ends of the gripper wheel and tension wheel arms 10 being linked together, and means remote from the fixed axes of said swingable arms for maintaining said swingable arms in their normal planes of movement respectively.

2. A fall rope carrier including in combination, two supporting cable traverse wheels rotatably mounted in fixed relation to each other for engaging the upper side of the supporting cable, a wheel mounted coaxially with and fixed to each cable traverse wheel 20 for engagement with the lower side of the driving line, a gripper wheel for engagement with the under side of the supporting cable and rotatably mounted in the free end of a swingable arm the other end of which is 25 rotatably mounted on an axis fixed relatively to the cable traverse wheels, a tension wheel for engagement with the upper side of said driving line and rotatably mounted in the upper end of a second swingable arm, the 30 free ends of the gripper wheel and tension wheel arms being linked together, and means remote from the fixed axes of said swingable arms for maintaining said swingable arms in their normal planes of movement 35 respectively.

3. A fall rope carrier including in combination, two supporting cable traverse wheels rotatably mounted in fixed relation to each other, a gripper wheel for engagement with the under side of the supporting cable and 40 rotatably mounted in the free end of a swingable arm, a tension wheel for engagement with the upper side of said driving line and rotatably mounted in the upper end of a second swingable arm, the free ends of the 45 gripper wheel and tension wheel arms being linked together, and means between said

swingable arms and said main frame for maintaining said arms in their normal planes of movement respectively. 50

4. A fall rope carrier including in combination, two supporting cable traverse wheels rotatably mounted in fixed relation to each other, a gripper wheel for engagement with the under side of the supporting cable and 55 rotatably mounted in the free end of a swingable arm, a tension wheel for engagement with the upper side of said driving line and rotatably mounted in the upper end of a second swingable arm, the free ends of the 60 gripper wheel and tension wheel arms being linked together, and a resistance bar fixed to said main frame and coacting with said swingable arms for preventing sidewise deflection of said swingable arms. 65

5. A fall rope carrier including in combination, two supporting cable traverse wheels rotatably mounted in fixed relation to each other for engaging the upper side of the supporting cable, a wheel mounted coaxially 70 with and fixed to each cable traverse wheel for engagement with the lower side of the driving line, a gripper wheel for engagement with the under side of the supporting cable and rotatably mounted in the free end of a 75 swingable arm the other end of which is rotatably mounted on an axis fixed relatively to the cable traverse wheels, a tension wheel for engagement with the upper side of said driving line and rotatably mounted in the 80 upper end of a second swingable arm, the free ends of the gripper wheel and tension wheel arms being linked together, and means between said swingable arms and said main frame for maintaining said arms in their 85 normal planes of movement respectively.

Signed at New York, in the county of New York and State of New York, this 20th day of Nov., 1912, before two subscribing witnesses.

JOHN T. HORTON.
